(57) **CLAIM**

The ornamental design for a lighting pod lens, as shown and described.

DESCRIPTION

FIG. 1 is a front, side perspective view of a lighting pod lens with an outer ring zoomed out from an inner lens showing our new design.

FIG. 2 is a bottom, perspective view thereof;

FIG. 3 is top, front perspective view thereof;

FIG. 4 is a bottom perspective view where the outer lens is flush with the inner lens; and,

FIG. 5 is a top perspective view where the outer lens is flush with the inner lens.

The broken lines depict environmental structure of the lighting pod lens and do not form any part of the claim.
